GUARDRAIL

Francis O. Heltzel, Youngstown, Ohio

Application November 28, 1936, Serial No. 113,205

7 Claims. (Cl. 256—13.1)

The invention relates to guardrails for use along highways to prevent vehicles from running off of the road at sharp turns or at the edges of steep grades or precipices, and more particularly to a semi-rigid sheet metal guardrail comprising formed sheet metal rails having their end portions overlapped and connected together and their brackets mounted upon supporting posts.

10 An object of the invention is to provide a guardrail of this character in which the rails are so shaped and mounted as to provide a semi-rigid construction sufficiently strong and durable to withstand the shocks incident to the impact of a vehicle while at the same time affording sufficient resilience to properly cushion the shock of impact so as to avoid serious damage to the contacting vehicle and injury to the occupants thereof.

20 Another object is to provide such a guardrail in which the rails are not placed under tension.

Another object is to provide a guardrail of this character in which the separate rails are so mounted that they will individually compensate for expansion and contraction due to changes in the temperature.

The above objects together with others which will be apparent from the drawing and following description or which may be hereinafter referred to, may be attained by constructing the improved guardrail in the manner illustrated in the accompanying drawing, in which

Figure 1 is a front elevation of one end portion of the improved guardrail embodying the invention;

Fig. 2, a plan view of the portion of the guardrail shown in Fig. 1;

Fig. 3, a vertical sectional view through a bracket upon one of the supporting posts showing the manner in which the adjoining ends of adjacent rails are connected to the bracket and to each other;

Fig. 4, a front elevation of the connected adjoining ends of adjacent rails;

Fig. 5, a vertical sectional view through a modified form of rail;

Fig. 6, a similar view of another modification of the rail; and

Fig. 7, a vertical sectional view through a modified form of the bracket.

Similar numerals refer to similar parts throughout the drawing.

In carrying out the invention posts 10 of any suitable material and design are set up at spaced intervals along the side of a road, the spacing of the posts depending upon the length of the rails. A bracket indicated generally at 11, formed of a heavy sheet or plate of steel, is connected to each post. This connection is preferably made by means of a single bolt indicated

at 12 passing through a horizontally disposed slot 13 centrally located in the bracket and of slightly greater width than the diameter of the bolt, as indicated in Figs. 3 and 4. The bolt may extend entirely through the post, being provided with a nut 14 at its rear end. This elongated slot is provided in the bracket merely to compensate for any slight error in the spacing of the posts so that a uniform spacing of the brackets, from center to center, may be maintained throughout the entire guardrail.

The central portion of each bracket is adapted to bear against the front face of the post and this portion may be of considerable height as indicated at 15 in Fig. 3 or may be only sufficient to accommodate the bolt 12 as indicated at 15a in Fig. 7. Above and below this central portion the ends of the bracket are flared forwardly away from the post, terminating in the vertical upper and lower edge portions 16, the free edges of which are preferably curved outward as at 17.

The flared portions referred to may be of substantially narrow width and at a slight angle to the horizontal as indicated at 18 in Fig. 3, or they may be of relatively greater width and at a considerable angle to the horizontal as indicated at 18a in Fig. 7.

The rails indicated generally at 19 are formed of sheet metal of considerably lighter gauge than the brackets and each rail, as shown in Figs. 1 to 4 inclusive, may comprise the central substantially vertical portion 20, above and below which the sheet is bent inward or rearward, preferably in a substantially reverse curve as indicated at 21, and then upward and downward respectively, in the substantially narrow vertical portions 22 corresponding in width and position to the portions 16 of the bracket, the upper and lower edges of the sheet terminating in the arcuate rearwardly concaved open beads or ribs 23 extending above and below the ends of the bracket and adapted to receive the forwardly curved end portions 17 of the bracket as shown in Fig. 3.

The ends of adjacent rails are overlapped as best shown in Figs. 3 and 4 and these overlapped ends of the rails are connected to each other and to the brackets by means of the bolts 24 located through the vertical portions 22 of the rails 16 of the bracket.

In order to compensate for expansion and contraction of the rails due to changes in temperature, spacing washers or collars 25 may be interposed between the front face of the bracket and the heads of the bolts 24, these collars being of slightly greater length than the combined width of the two overlapped end portions of the rails. Each collar may have a slight clearance around its respective bolt 24 and the outer diameter thereof is considerably less than the apertures 26 in the rails whereby the end portions of the rails 60

may move longitudinally upon said collars as the rails expand and contract.

The central portions 20 of the overlapped ends of the rails may be further connected together by bolts 24a similar to the bolts 24 surrounded by collars or washers 25a similar to the collars 25 above described.

As shown in Fig. 5, the rail 19a may have the upper and lower vertical portions and the arcuate edge portions 22a and 23a respectively, identical with the corresponding portions above described while the central portion 20a may be of only sufficient width to accommodate the connecting bolts, the rail being flared rearwardly above and below said central portion to the portions 22a, as indicated at 21a.

In Fig. 6 the rail may be of exactly the construction illustrated in Figs. 3 and 4 with the exception that the central portion 20b is rearwardly depressed at its center as at 20c to receive the central attaching bolts.

Each end post of the guardrail may be set slightly further back from the road than the remaining posts as indicated at 10a in Figs. 1 and 2 and a short, rearwardly curved rail section 27 may be connected to the bracket of said post and to the overlapped end of the adjacent rail 19 in the manner above described and the forms in said curved guardrail section may die out toward the rear or outer end thereof, as indicated at 28.

From the above it will be seen that a semi-rigid guardrail is produced which need not be placed under tension in order to provide sufficient resilience to properly cushion the impact of a vehicle thereon. The flared portions 18 and 21 of the bracket and rails respectively will provide sufficient spring in the entire structure to permit the guardrail to absorb or cushion the impact and then spring back to its normal position and the curved ends 17 of the bracket will support the strengthening beads or ribs 23 at the upper and lower edges of the rails.

It will further be seen that any of the forms of rails disclosed herein may be used with either form of bracket without requiring any change in the construction or assembling of either.

It will be seen that when a vehicle strikes this guard rail, there will be no deflection and the vehicle will not be thrown back into the line of traffic due to the backlash which is produced with other forms of sheet metal guardrails which are held under tension. No dead end anchorage is required for this type of guardrail and there are no complicated or costly intermediate or end connections to get out of order.

The entire guardrail is easier to erect, there are fewer parts and a damaged rail can be replaced without disturbing any other rail.

The curved upper and lower edges of the rail not only assist in strengthening the same, but prevent serious injury to a person thrown clear of a vehicle striking the rail and also reduce the chances of damage to the vehicle.

The manner in which the rails are formed prevents their warping or sagging so that they will always remain in a true line, thus making a safer guardrail.

I claim:

1. A road guard including a series of spaced posts, metal brackets connected at their center portions to the posts and having their upper and lower end portions offset forwardly away from the posts, sheet metal rails having their upper and

lower portions connected to the forwardly offset portions of the brackets, and rearwardly open beads formed at the upper and lower edges of the rails, the upper and lower ends of the brackets being forwardly curved and received in said beads.

2. A road guard including a series of spaced posts, metal brackets connected at their center portions to the posts, each bracket having a central, vertical, flat portion, forwardly disposed portions above and below said central portion and vertical, flat upper and lower end portions, and sheet metal rails having their upper and lower portions connected to the flat upper and lower end portions of the brackets.

3. A road guard including a series of spaced posts, metal brackets connected at their center portions to the posts, each bracket having a central, vertical, flat portion, forwardly disposed portions above and below said central portion and vertical, flat upper and lower end portions, and sheet metal rails having their upper and lower portions connected to the flat upper and lower end portions of the brackets, said rails having their central portions forwardly offset.

4. A road guard including a series of spaced posts, metal brackets connected to the posts, sheet metal rails having their end portions overlapped and provided with elongated apertures, washers having spacing collars longer than the combined thickness of said overlapped end portions of the rails and located through said apertures, bolts located through said washers, and nuts upon said bolts.

5. A road guard including a series of spaced posts, metal brackets connected at their center portions to the posts, each bracket having a central, vertical, flat portion, forwardly disposed portions above and below said central portion and vertical, flat upper and lower end portions, and sheet metal rails each having a forwardly offset central portion, rearwardly disposed portions above and below said central portion and vertical, flat upper and lower edge portions connected to the flat upper and lower end portions of the brackets.

6. A road guard including a series of spaced posts, metal brackets connected at their center portions to the posts, each bracket having a central, vertical, flat portion, forwardly disposed portions above and below said central portion and vertical, flat upper and lower end portions, and sheet metal rails each having a forwardly offset central portion, rearwardly disposed portions above and below said central portion and vertical, flat upper and lower edge portions connected to the flat upper and lower end portions of the brackets, and rearwardly open beads formed at the upper and lower edges of the rails, the upper and lower ends of the brackets being forwardly bent and received in said beads.

7. A road guard including a series of spaced posts, metal brackets connected at their center portions to the posts, each bracket having a central, vertical, flat portion, a forwardly and upwardly disposed portion above said central portion terminating in an upwardly disposed, vertical, flat end portion, a forwardly and downwardly disposed portion below said central portion terminating in a downwardly disposed, vertical, flat end portion, and sheet metal rails having their upper and lower portions connected to the flat upper and lower end portions of the brackets.

FRANCIS O. HELTZEL.
